UNITED STATES PATENT OFFICE.

WILLIAM G. ADAMS, OF ROANOKE, VIRGINIA.

SAFETY RAZOR.

Application filed March 9, 1923. Serial No. 623,992.

To all whom it may concern:

Be it known that I, WILLIAM G. ADAMS, a citizen of the United States, residing at Roanoke, in the county of Roanoke and State of Virginia, have invented a new and useful Improvement in Safety Razors, of which the following is a specification, reference being had to the accompanying drawing.

My improvement relates to a safety razor structure wherein provision is made for conveniently turning the blade so as to bring first one side and then the other side of the blade against the face during the shaving operation, whereby the blade may longer be kept in cutting condition.

A structure for this purpose is described in my application for Letters Patent, Serial Number 578,377, filed July 29, 1922. In the form described by that application, the blade carrier member turns on an axis which extends in the direction of the length of the handle of the structure. The object of the present invention is to provide a structure in which the axis of the carrier member is parallel to the cutting edge of the blade.

In the accompanying drawings;

Fig. 1 is a side elevation of a safety razor embodying my improvement;

Fig. 2 is an elevation of the same structure looking toward the left as shown in Fig. 1, the greater part of the handle being broken away;

Fig. 3 is an upright section on the line, 3-3, of Fig. 1, looking toward the right;

Fig. 4 is a section on the line, 4-4, of Fig. 1;

Fig. 5 is a perspective of another form of the structure;

Figure 6 is a rear elevation of the same structure, portions being broken away;

Fig. 7 is an upright section on the line, 7-7, of Fig. 5, the yoke-form carrier member being turned away from the guard and the blade and the blade holder being turned transversely to the plane of the carrier member;

Fig. 8 is a detail view of the yoke-form carrier and the blade holder;

Fig. 9 is a section on the line, 9-9, of Fig. 5.

Referring to said drawings, A is the usual handle. B is the guard support which rises obliquely from the upper end of the handle. C is the guard. In the form shown by the drawings, the guard is integral with the support B. D is the blade having a back,

D¹, which is engaged in the blade holder, E. Said holder is pivoted to the carrier member, F, on an axis which is midway between the ends of the blade and perpendicular to the cutting edge of the blade and parallel to the plane of the blade. The holder, E, has a journal, E¹, resting in a bearing, F¹, formed in the carrier member, F. At the side of the holder opposite said bearing the holder has a head or handle, E², adapted to be grasped by the hand for turning the holder in said bearing.

On the support, B, are two bearings, B¹, formed by cutting a tongue from each side edge of the support and bending said tongues backward, whereby the axial line of the two bearings is placed outside of the body formed by the support and the guard. The carrier member is of the same length as the length of the guard—the dimension of the guard parallel to the carrier member. At each end the carrier member has in its lower part an eye, F¹, through which the tongue forming the adjacent bearing extends. By this means the carrier member is hinged to the unitary body composed of the support, B, and the guard, C.

At the middle of the carrier, F, a tongue, F², extends downward into a slot or aperture, B², formed in the adjacent part of the support, B. On the inner face of the support, B, is a blade spring, B³, secured to the support by rivets, B⁴. The middle part of said spring extends into the path of the tongue, F², and presses said tongue rearward, the contact between the spring and said tongue being below the axial line of the bearings, B¹, whereby strain is exerted upon the carrier member in the direction which causes the blade, D, to be pressed against the guard, C, when the carrier member and the blade are in the working position.

When the blade is to be reversed, the carrier member is turned rearward against the action of the spring, B³, until the blade is in the upright position, as shown by dotted lines in Fig. 1. Then, by grasping the handle, E², the holder, E, and the blade, D, are turned half-way on the axis of the journal, E¹. When that has been done, the carrier member and the holder and the blade are again turned on the axial line of the bearings, B¹, into the working position.

The guard and the blade and the blade back may be of any ordinary construction.

In the form illustrated by Figs. 5, 6, 7, 8

and 9, the carrier member is hinged on a line which is parallel to and near the cutting edge of the blade, the carrier member being in the form of a yoke within and by 5 which the holder is held rotatably.

In said form we have the handle, A, the support, B, and the guard, C, as before. The yoke-form carrier member, G, has arms, G¹, extending along the ends of the guard 10 and hinged at, G², to the forward part of the guard, in a line parallel to and a little forward of the cutting edge of the blade, D. The blade back, D¹, is engaged by three tongues, H¹, forming parts of the holder, H, 15 two of said tongues being at one side and the other at the other side of said back. The holder has a journal, H², resting in a bearing, G³, formed in the carrier member. Outside of said bearing said journal supports a head or handle, H³. To the rear of the support, B, are secured two spring tongues, G⁴, which extend into the path of and engage the body of the yoke-form carrier member when the latter is in its working 20 position, at which time the blade, D, is also in its working position, its cutting edge bearing against the guard.

When the blade is to be reversed, the rear part of the yoke-form carrier member is 30 pressed upward out of engagement with the tongues, G⁴, and forwarded into the position indicated by dotted lines in Fig. 7. Then the holder, H, and the blade are turned half-way by the hand engaging the handle, H³, 35 this turning being on the axis of the journal, H², and the bearing, G³. When this half-turn has been made, the yoke-form carrier member is again drawn backward into engagement with the tongues, G⁴.

40 It will now be observed that in each of these two forms, the carrier member is hinged on an axis which is parallel to the cutting edge of the blade, the hinge line in one case being at the rear of the blade and in the other case being near and at the front of the blade. It will also be observed that in each form the blade may be reversed without detaching the blade from the remainder of the structure.

50 I claim as my invention,

1. In a safety razor, the combination with a support and a guard, of a carrier member hinged for tilting on a line located parallel to the cutting edge of the blade and far 55 enough to allow the blade to clear the guard while the below-mentioned holder is being rotated, a holder hinged midway between its ends to the carrier member on an axial line transverse to the hinge line of the carrier member and approximately parallel to the plane of the blade, means for holding the carrier member in the working position, and a blade held by said holder, substantially as described.

60 2. In a safety razor, the combination with

a support and a guard, of a carrier member hinged for tilting on a line located parallel to the cutting edge of the blade and far enough to allow the blade to clear the guard while the below-mentioned holder is being 70 rotated, a holder hinged midway between its ends to the carrier member on an axial line transverse to the hinge line of the carrier member and approximately parallel to the plane of the blade, yielding means for holding the carrier member in the working position, and a blade held by said holder, substantially as described.

3. In a safety razor, the combination with a support and a guard, of a carrier member 80 hinged for tilting on a line located parallel to the cutting edge of the blade and below the plane of the blade, a holder hinged midway between its ends to the carrier member on an axial line transverse to the hinge line 85 of the carrier member and approximately parallel to the plane of the blade, means for holding the carrier member in the working position, and a blade held by said holder, substantially as described. 90

4. In a safety razor, the combination with a support and a guard, of a carrier member hinged for tilting on a line located near the rear of the blade and parallel to the cutting edge of the blade and far enough to allow 95 the blade to clear the guard while the below-mentioned holder is being rotated, a holder hinged midway between its ends to the carrier member on an axial line transverse to the hinge line of the carrier member and approximately parallel to the plane of the blade, means for holding the carrier member in the working position, and a blade held by said holder, substantially as described. 100

5. In a safety razor, the combination with 105 a support and a guard, of a carrier member hinged for tilting on a line located near the rear of the blade and parallel to the cutting edge of the blade and far enough to allow the blade to clear the guard while the below-mentioned holder is being rotated below the plane of the blade and a holder hinged midway between its ends to the carrier member on an axial line transverse to the hinge line 110 of the carrier member and approximately 115 parallel to the plane of the blade, means for holding the carrier member in the working position, and a blade held by said holder, substantially as described.

6. In a safety razor, the combination with 120 a support and a guard, of a carrier member hinged for tilting on a line located parallel to the cutting edge of the blade and near the rear of the blade, a holder hinged midway between its ends to the carrier member on an axial line transverse to the hinge line of the carrier member and approximately parallel to the plane of the blade, means engaging the carrier member below said hinge line for holding the carrier member in the work-

ing position, and a blade held by said holder, substantially as described.

7. In a safety razor, the combination with a support and a guard, of a carrier member hinged for tilting on a line located parallel to the cutting edge of the blade and near the rear of the blade and the carrier having a downward-extended tongue, a holder hinged midway between its ends to the carrier member on an axial line transverse to the hinge line of the carrier member and approximately parallel to the plane of the blade, yielding means bearing against said tongue for holding the carrier member in the working position, and a blade held by said holder, substantially as described.

8. In a safety razor, the combination with a handle and a support and a guard and a blade, of means including a journal and a handle for supporting the blade for turning the blade on an axial line which is transverse to the length of the blade and to the line of the handle, substantially as described.

9. In a safety razor, the combination with a handle and a support and a guard and a blade, of means for supporting the blade for turning the blade on an axial line which is

transverse to the length of the blade and also on a line which is parallel to the length of the blade, said means including a journal and a handle, the latter to be grasped by the hand, substantially as described.

10. In a safety razor, the combination with a handle and a support and a guard, of a blade, a holder, and a member joined to the holder between the ends of the holder and on an axial line which is transverse to the length of the blade and to the line of the handle, said member including a journal and a handle, the latter to be grasped by the hand, substantially as described.

11. In a safety razor, the combination with a handle and a support and a guard, of a blade, a holder, and a member rigidly joined to the holder between the ends of the holder and on an axial line which is transverse to the length of the blade and to the line of the handle, said member including a journal and a handle, the latter to be grasped by the hand, substantially as described.

In testimony whereof I have signed my name, this 8th day of March, in the year one thousand nine hundred and twenty-three.

WILLIAM G. ADAMS.
